UNITED STATES PATENT OFFICE

2,075,142

BRAUN TUBE

Kurt Schlesinger, Berlin, Germany

Application October 18, 1933, Serial No. 694,135
In Germany October 21, 1932

4 Claims. (Cl. 250—27.5)

Heretofore it has been assumed that the deflecting potentials necessary for acting on the image screens of Braun tubes are dependent in substance on the arrangement and embodiment 5 of the deflecting plates, and that by increasing the deflecting potential an improved effect may be obtained.

The applicant has found that the potential necessary for the operation of Braun tubes is determined solely by the dimensions of the bulb of 10 the tube and by the anode potential. This optimum potential—upon an increase of which an improved effect does not take place—may be calculated according to the formula

$$E_p = \frac{1}{2} E_a \cdot \frac{D^2}{L^2}$$

wherein E_p is the plate deflection potential, E_a the anode potential, D the diameter of the image 20 screen, and L the length of the tube.

For a tube of 30 cm. in length and 20 cm. in diameter of the image screen there results with an E_a of 1500 volts;

$$E_p = \frac{1}{2} \cdot 1500 \cdot \frac{20^2}{30^2} = \text{approximately 335 volts}$$

According to the invention, the plate deflection potentials should be provided with values approximately agreeing with those resulting from 30 the above formula, and should in no way exceed the same to an appreciable extent.

Television images produced with the known Braun tubes do not possess the requisite rectangular form, but are rather more of a substantially 35 trapezoidal shape disclosing corresponding distortions of the contents of the picture in a horizontal direction.

The applicant has ascertained that these disturbances are caused by marginal field effects of 40 the pairs of deflecting plates on each other, and that it is possible by suitable arrangement and dimensioning of the plates to preclude this disturbing effect and to produce completely rectangular images.

The strength and accordingly the influence of the marginal fields is determined by the ratio between the spacing of the plates of the single pairs and the spacing between the pairs of plates 45 themselves.

According to the invention, the ratio between the spacing of the pairs of plates in relation to each other and the spacing of the plates themselves is selected to be equal to or greater than 3 55 (the essential feature in this connection is the

spacing at the rear end of the front deflecting plates).

In order now to permit of a construction of the system as compact as possible it is desirable in accordance with the invention to provide the deflecting plates with a certain tilt in relation to each other. In this connection—particularly if the plates are relatively short (for example 15 mm.)—the one plate may be arranged parallel to the axis, and the other plate furnished with 10 a certain inclination in relation to the first plate, whereby a considerable simplification in the construction of the system is obtained.

This arrangement is particularly suitable in connection with tubes with a so-called bending of the ray, i. e., in the case of tubes in which between the anode and the first pair of deflecting plates there is provided a deflecting element imparting a constant preliminary deflection to the cathode ray. In this case the tilt of the one 15 deflecting plate of both systems in relation to the second plate parallel to the axis may be selected in such fashion that the preliminarily deflected ray enters the deflecting systems approximately parallel to the tilted plate.

It has been found to be convenient to employ plates of approximately 15 mm. in length, and to select the spacing of the front edges of the plates at approximately 5 mm. and that of the rear 20 edges of the plates at approximately 1.5—2 mm.

A particular advantage of this arrangement resides in the fact that it is possible by altering the inclination of the plates to vary the sensitivity (i. e., the movement in mm. per volt of deflecting potential) within wide limits, without varying at the same time the size of the image.

The invention is illustrated by way of example in the drawing,

Fig. 1 of which shows the neck portion of a Braun tube according to the invention, incorporating the electrode system, whereas

Fig. 2 shows the conically enlarged portion of the tube and should be read as the right hand continuation of Fig. 1.

In the drawing, 1 is the wall of the tube, 2 the Wehnelt cylinder, which is secured to the holder 3 and within which there is arranged the cathode 4, 5 a preliminary anode, 6 a concentration cylinder and 7 the after-acceleration anode. 8 is the deflecting element, which is composed of two angle plates 20 and 21, and which imparts to the ray a constant preliminary deflection. The plate 20 of this element is conductively connected with the anode, whilst the plate 21 receives in relation 45 50 55

to the plate 20 a constant bias from the battery 16. 9 and 12 are the two pairs of deflecting plates. The plates 10 and 13 are linked up with the same potential as the plate 21, whilst the plates 11 and 5 14 receive the deflecting potentials from the generators 18 and 19. The plates 10 and 13 are disposed parallel to the axis, whilst the plates 11 and 14 are tilted in relation to the axis, which is so chosen that the preliminarily deflected ray 10 enters the system approximately parallel to this plate. Since the plates 10 and 13 possess a strongly positive bias—which conveniently may be greater than the maximum deflection amplitude occurring—the total so-called cross-current will 15 be attracted towards these plates, whilst the actual control plates 11 and 14 remain absolutely free of cross-current.

The tube according to the invention is devoid of "cross" and cross-current defect, and permits 20 of the production of images completely free of distortion with the smallest application of potential.

I claim:

1. A Braun tube for television purposes which 25 comprises an evacuated envelope, a cathode and an anode arranged in operative relationship thereto, a Wehnelt cylinder surrounding said cathode, a picture receiving screen, one pair of deflecting plates arranged between said anode and said screen, and a further pair of deflecting plates arranged between the first said pair and the screen, said two pairs facing one another, characterized in that at least the plates of the further said pair of deflecting plates are inclined 30 with respect to one another and that the distance between said two pairs of deflecting plates is at least three times as great as the distance between the plates of the further said pair at the end facing said anode.
2. A Braun tube for television purposes which 35 comprises an evacuated envelope, a cathode and an anode arranged in operative relationship thereto, a Wehnelt cylinder surrounding said cathode, a picture receiving screen, one pair of deflecting plates arranged between said anode 40 and said screen, and a further pair of deflecting plates arranged between the first said pair and the screen, said two pairs facing one another, characterized in that the plates of the further said pair of deflecting plates are inclined with respect to one another, and that the distance between said two pairs of deflecting plates is at least three times as great as the distance between the plates of the further said pair of deflecting plates at the end facing the anode.

and said screen, and a further pair of deflecting plates arranged between the first said pair and the screen, said two pairs facing one another, characterized in that means are arranged between said anode and the first said pair of deflecting plates for imparting a constant deflection to the ray in two directions, perpendicular to one another, that at least the plates of the further said pair of deflecting plates are inclined with respect to one another, and that the distance between said two pairs of deflecting plates is at least three times as great as the distance between the plates of the further said pair of deflecting plates at the end facing the anode.

3. A Braun tube for television purposes which 15 comprises an evacuated envelope, a cathode and an anode, arranged in operative relationship thereto, a Wehnelt cylinder surrounding said cathode, a picture receiving screen, and two pairs of deflecting plates arranged between said anode and said screen, said two pairs facing one another, characterized in that the plates of at least one pair of deflecting plates have a length of approximately 15 mm. and a distance of at least 20 1.5 mm. from one another at their ends facing the anode, and a distance of at least 4 mm. from one another at their ends facing the screen, and that the distance between said two pairs of deflecting plates is at least three times as great as the distance between the plates of the pair of 25 deflecting plates which is arranged next to said screen at the end facing said anode.

4. A Braun tube for television purposes which 30 comprises an evacuated envelope, a cathode and an anode arranged in operative relationship thereto, a Wehnelt cylinder surrounding said cathode, a picture receiving screen and two pairs of deflecting plates mounted in axial consecution to each other without any further element being disposed therebetween, characterized in that the 35 distance between said pairs of deflecting plates is at least three times as great as the distance between the two plates of each of said pairs of deflecting plates.
